UNITED STATES PATENT OFFICE.

MARY PURVIS, OF PLAINVIEW, MINNESOTA.

RINSING AND DRYING DEVICE FOR DISHES AND OTHER ARTICLES OF TABLE USE.

SPECIFICATION forming part of Letters Patent No. 364,602, dated June 7, 1887.

Application filed March 1, 1887. Serial No. 229,350. (No model.)

To all whom it may concern:

Be it known that I, MARY PURVIS, of Plainview, in the county of Wabasha and State of Minnesota, have invented a new and Improved 5 Rinsing and Drying Device for Dishes and other Articles of Table Use, of which the following is a full, clear, and exact description.

This invention has, mainly, for its object the drying or rinsing and drying of dishes, plates, 10 cups and saucers, spoons, knives and forks, and other articles of table use; and it consists in a novel utensil for the purpose, substantially as hereinafter described, and pointed out in the claims. It is designed to be used after 15 the dishes or other articles have been washed, and its function is more particularly that of drying the same without having resort to wiping, thus saving towels and proving a great economy in point of time and labor, besides 20 doing the work more satisfactorily than wiping with a towel does.

Reference is to be had to the accompanying drawings, forming a part of this specification, in which similar letters of reference indicate 25 corresponding parts in all the figures.

Figure 1 represents a plan of the utensil; Fig. 2, a vertical section of the same upon the line *xx* in Fig. 1, and Fig. 3 a vertical section upon the line *yy* in Fig. 1.

30 A is a circular vessel or outer case, made of tin, of which material the other parts may also be made, if desired. Said outer case, which may be of any required diameter and about four inches (more or less) deep, is open 35 at its top and formed with a shelving or dished bottom, *b*, having an opening, *c*, in its center for the escape of water from the utensil.

When the utensil is being used, it is stood 40 in a pan, for which purpose the case A is provided with any number of legs, *d*. Within this outer case or vessel, A, is loosely slipped or fitted an open-work tray, which rests upon where the bottom and sides of the case A meet, or upon suitable jogs at such point for the 45 purpose. This tray, which is of circular form, corresponding to the rim or side portion of the vessel, is composed of an outer rim, *e*, and central inner rim, *f*, leaving an aperture, *g*, in the center of the tray, and of two opposite flat 50 racks, B B, and two intermediate downwardly and inwardly sloping racks, C C, also on opposite sides of the inner rim, *f*, and inclining, so that their inner and outer ends project a little above and below the flat racks B B, the 55 removable tray thus constituting a compound

rack, one pair of racks being transverse to the other pair, and all joined or connected with the inner and outer rims, *e f*. Said racks are mainly composed of galvanized wire of suitable strength.

60 Mounted on and fast to the center portion of the bottom *b* of the case A, by legs *h h*, which pass up through the aperture *g* in the compound rack or tray, is a tubular receptacle, D, provided with a sieve-like or perforated 65 bottom, *i*.

70 To use the utensil, it is stood by its legs *d* in a pan, and the dishes and plates, as or after they are washed, are stood up in the racks B B, leaning upon one another and upon or against the tubular receptacle D, while the cups and saucers are placed upon the inclined racks C C, which, by their slope, facilitate 75 draining. The tubular receptacle D serves to hold spoons and knives and forks.

75 After the articles to be dried have been washed and placed in or on their respective portions or racks and tubular receptacle of the utensil, as described, hot water is poured over them, which drains or runs out through the 80 aperture *c* into the pan in which the utensil stands, and in a very short time the articles may be removed from the utensil thoroughly dry and cleaned much more satisfactorily than if wiped with a towel, and at an expenditure of 85 much less time and labor.

When necessary to clean the receptacle D or vessel A, the tray of racks B and C is lifted out and afterward replaced for subsequent use.

90 Having thus fully described my invention, what I claim as new, and desire to secure by Letters Patent, is—

A drier or rinser and drier for dishes and other articles of table use, consisting of the 95 outer case or vessel, A, having a sloping apertured bottom, *b*, and legs *d d*, the elevated central tubular receptacle, D, having a sieve-like bottom, *i*, and the removable tray or compound rack, composed of two flat racks, B B, 100 and two intermediate inclined racks, C C, in transverse relation with the flat racks, and all arranged to leave a central aperture, *g*, adapted to admit of the tray being passed over the elevated receptacle D, substantially 105 as shown and described.

MARY PURVIS.
